CLAIM

The ornamental design for a tread for a glove, as shown and described.

DESCRIPTION

FIG. 1 is a front elevational view of a tread for a glove showing my new design, the rear of the tread being a mirror image thereof;

FIG. 2 is a side elevation view thereof;

FIG. 3 is the other side elevational view thereof;

FIG. 4 is a top plan view thereof;

FIG. 5 is a bottom plan view thereof;

FIG. 6 is a front elevational view of another embodiment thereof, the rear of the tread being a mirror image thereof;

FIG. 7 is an opposite side elevational view thereof;

FIG. 8 is an opposite side elevational view thereof;

FIG. 9 is a top plan view thereof; and

FIG. 10 is a bottom plan view thereof.

The broken line showing of the glove is for illustrative purposes only and forms no part of the claimed design.

FIG. 2

FIG. 1

FIG. 3

FIG. 4

FIG. 5

FIG.7

FIG.6

FIG.8

FIG.9

FIG.10
